UNITED STATES PATENT OFFICE.

AUGUST H. LEIPERT, OF NEW YORK, N. Y., ASSIGNOR TO INTERNATIONAL MOTOR COMPANY, OF NEW YORK, N. Y., A CORPORATION OF DELAWARE.

AUTOMOBILE RADIATOR.

1,403,860.

Specification of Letters Patent. Patented Jan. 17, 1922.

Application filed May 27, 1920. Serial No. 384,516.

To all whom it may concern:

Be it known that I, AUGUST H. LEIPERT, a citizen of the United States, residing in the borough of Queens of the city of New York, 5 in the State of New York, have invented certain new and useful Improvements in Automobile Radiators, of which the following is a specification, reference being had to the accompanying drawings, forming a part 10 hereof.

The objections to the use of belt driven fans as mechanical cooling agents for cooling radiators have long been recognized. The wear to which fan belts are subjected 15 causes their disintegration, the power required to drive a fan is very appreciable, introducing an added factor of inefficiency, and the actual danger resulting from the breaking of a fan belt is not inconsiderable, 20 especially when the fan as in many motor trucks is located near the floor board. Many efforts have been made to provide self-contained fan units as a part of the fly-wheel and other expedients have been used, but 25 such efforts have not been the best solutions since usually they require reconstruction and rearrangement of many of the parts now adopted as standard design.

The present invention has for its object 30 to provide an improved automobile radiator which shall have associated with it a cooling fan of such structure as will permit its ready incorporation in motor trucks of standard design without the changing of any of the 35 parts or their rearrangement, and will serve as an effective and highly efficient cooling medium. In accordance with the invention the radiator is mounted in rear of the motor and directly in front of the dash and has 40 imperforate front and rear walls which form air channels extending downwardly to a point beneath the floor board. This radiator is mounted in a particular relation to the fly-wheel and to a fan ring carried there- 45 by, the blades of the fan ring being of such peculiar construction and relation and in such disposition to the air channels as to bite the air and create constant circulation across the tubes by a combined centripetal 50 and centrifugal action on the air. This is the essence of the invention. One suitable embodiment thereof is illustrated in the accompanying drawings, in which—

Figure 1 is a view in vertical section of an 55 improved radiator showing in side elevation

the improved fan therefor, all of the parts being indicated in their relation to the motor and dash of a truck.

Figure 2 is a view in front elevation of the 60 improved radiator.

Figure 3 is a view in plan thereof.

Figures 4 and 5 are fragmentary detail 65 views on a larger scale showing the fan ring and one of the blades thereon.

As shown in Figure 1 the improved radi- 70 ator *a* is mounted in accordance with the practice now prevalent in some types of trucks, in rear of the motor *b* and immediately in front of the dash *c*.

The radiator tubes *a'* are exposed at the sides of the radi- 75 ator for free inflow of air across them for cooling of the circulating water. These tubes are enclosed between an imperforate front wall *a²* and an imperforate rear wall *a³*, so that the air is drawn in only from 80 the sides across the tubes and is subject to the greatest suction action by the fan in the confined space. The front wall *a²* extends downwardly and embraces the fly-wheel *d* on the propeller shaft *e* so that the direc- 85 tion of flow of the air downwardly is well controlled and the air is confined against general diffusion. On the rear face of the fly-wheel is bolted a fan ring *f* which may be of light cast metal, such as aluminum 90 and in this ring are provided through slots *f'* of suitable inclination to radial lines, these slots being adapted to receive the heels of fan blades *g*. Bolts *g'* may be passed through the fan blades and the rings to se- 95 cure the blades in position. As shown in Figure 4 the blades are of peculiar type having lips *g²* which extend beyond the face of the ring *f* and into the air space directly beneath the confining walls *a²*, *a³*, so as to bite the air and cause its circulation in a manner to be described. The blades may have secured to their edges an angle ring *h* which rests in such intimate proximity to the edge of the walls *a²*, *a³* as to further con- 100 fine the air and make it essentially subject to the action of the biting edges *g²* of the blades *g*.

The angular position of the blades *g* to radial lines of the ring *f* are such that when 105 the fly-wheel rotates and the biting edges *g²* of the blades revolve around the confined space formed by the casing about the fly-wheel *d*, air will be drawn continuously and rapidly across the tubes *a'* and downwardly 110

towards the axis of rotation of the ring f , the general effect appearing to be one of centripetal action. When the air is thus drawn downwardly and towards the axis of rotation of the ring f it is further acted on by the blades g and thrown outwardly with what appears to be a centrifugal action. Whatever the theory may be, however, the result is that a strong steady circulation of air is secured with a minimum consumption of power by the fan action and the water within the radiator tubes is cooled as effectively and with much greater efficiency than has been possible with the use of a belt driven fan. The parts as described and related admit of the ready installation of radiators of this type in old truck constructions without necessitating the change or rearrangement of any of the standardized elements. Further, for new constructions the improved radiator lends itself to comparatively inexpensive and ready assembling and installation and provides for the elimination of the accessory element necessary where a belt driven fan is employed. All elements of danger are eliminated and the annoyance of replacement of parts is removed.

As stated hereinbefore, efforts have been made to solve the cooling problem by providing self-contained fan units, but it has been

found in practise that such constructions are either inefficient or impracticable in that they require reorganization of many of the elements of a standardized form of truck. Further it has been found that the peculiar relation of fan blades and fan ring to the confining air channels, as illustrated herein, is conducive to the best results.

I claim as my invention:

1. In combination with a radiator having front and rear imperforate walls, a closed channel leading downwardly from the radiator, a fly-wheel disposed within the channel in substantially the plane of the radiator, a fan ring secured to the face of the fly-wheel, and fan blades mounted on the fan ring and disposed at one side of the plane of the channel but having their edges disposed within the channel.

2. A fan for automobile radiators comprising a ring secured to the fly-wheel of the motor and having inclined slots through its face, fan blades having their bases extending through the slots, and means to secure the blades within the slots, the said blades being inclined radially and having biting edges to draw the air centrally to the ring and throw it out radially therefrom.

This specification signed this 13th day of May A. D., 1920.

AUGUST H. LEIPERT.
